UNITED STATES PATENT OFFICE

104,269

DESIGN FOR A HOSE GUARD

Theodore N. Kuleff, Valparaiso, Ind.

Application February 8, 1936, Serial No. 61,038

Term of patent 7 years

To all whom it may concern:

Be it known that I, Theodore N. Kuleff, a citizen of the United States, residing at Valparaiso, in the county of Porter, State of Indiana, have invented a new, original, and ornamental Design for a Hose Guard, of which the following is a specification, reference being had to the accompanying drawing, forming a part thereof.

Figure 1 is a top plan view.

Figure 2 is a side elevation of the hose guard.

Figure 3 is an end elevation.

I claim:—

The ornamental design for a hose guard as shown.

THEODORE N. KULEFF.
